UNITED STATES PATENT OFFICE

HARRY EHLIG, OF PEARL RIVER, NEW YORK, ASSIGNOR TO DEXTER FOLDER COMPANY, OF NEW YORK, N. Y., A CORPORATION OF NEW YORK

SHEET FEEDER

Application filed September 13, 1928. Serial No. 305,643.

My invention relates to improvements in sheet feeders for automatically separating and advancing successive sheets of paper or other impression-receiving material to printing, folding or ruling machines, or to such other types of machines as are devised to operate thereafter on such sheets.

The objects of my invention are, among other things, mainly to provide a sheet-feeder of this character having a simplified design which will have embodied therein separate mechanisms capable of performing efficient work, while they are not likely to get out of order, yet are very sensitive in action, all being incorporated in a feeder which will invariably separate and then feed or advance the successive sheets from a pile or bank of paper, but preferably from a fanned-out bank of paper on the feed-board, both automatically and with great rapidity.

With these objects in view, I have devised an improved front-edge sheet feeder which will separate and advance the sheets in a continuous spaced-apart flow by novel sheet separating and forwarding devices operating on the front portion or margins of the stacked-up sheets, comprising an improved suction feeding-off device operating in conjunction with an endless looped belt having spaced-apart perforations therein, whereby the superposed sheets are separated and advanced one by one in regular succession to the usual feed-rollers, coupled with a manually-operated tripping mechanism for stopping the movements of the suction devices coacting with the perforated belt as well as for stopping the revolution of the belt itself.

A further feature of my invention is to embody with such perforated suction-belt which is continuously operated in a forward direction, novel mechanisms whereby the suction is continuously applied to the suction shoe chamber and thence through the perforations in the belt, yet such suction feeding-off devices are operable only intermittently to enable the successive sheets to be separated and advanced in proper spaced relation with one another. By my improvements it is not necessary to control the timing or duration of the suction which is customarily applied in-

intermittently to the feeding-off devices, but only the movements of mechanisms by which the suction is applied to the sheets through the suction shoe and the perforations in the continuously moving belt.

My improved sheet-feeder also embodies other advantageous features of novelty and improvement in which the different operating parts are greatly simplified in form and action, and are made more effective and otherwise better adapted for use, all of which will be hereinafter described and then particularly set forth in the appended claims.

The drawings show my improvements in their preferred embodiment in a continuous sheet-feeder; such improvements, however, are not to be restricted to any particular type of sheet-feeder, as the invention may be embodied in various forms of feeders with similar advantages and results.

Of the drawings, Fig. 1 is an end elevation of my feeder looking rearwardly from the delivery end of the machine and showing the general arrangement of the various parts and mechanisms embodied therein;

Fig. 2 is a side view looking from the right of Fig. 1;

Fig. 3 is a sectional view on line 3-3 of Fig. 1;

Fig. 4 is a detail view of the drive wheel for the perforated belt;

Fig. 5 is a plan view of a portion of the belt on the drive wheel;

Fig. 6 is a side view partly in section of a modified form of the suction shoe and coacting devices that operate with the perforated belt;

Fig. 7 is an enlarged end view, partly in section, of the suction shoe looking from the left of Fig. 6;

Fig. 8 is a view similar to Fig. 6, but of another modified form of suction shoe and perforated belt;

Fig. 9 is a plan view of the belt and drive shown in Fig. 8;

Fig. 10 is a detail view, partly in section, of another modified form of a suction shoe and belt;

Fig. 11 is a section taken on the line 11-11 of Fig. 10; and

Fig. 12 is a detail sectional view of the suction shoe shown in Fig. 10 in partly operative position.

Similar numerals refer to similar parts through the several figures.

Referring to Figs. 1, 2 and 3, the two side-frames 13 and 14 of the feeder proper are arranged on either side of the lower feed-board 15 over which travel a series of feed belts 16 to advance the bank of sheets 17 along the feed-board 15. The belts 16 pass around the drum 18 fast to the cross shaft 19 journaled in the side frames 13 and 14.

In the present embodiment the sheet separating and advancing device comprises the endless loop belt 20 having spaced-apart perforations 21 cut therin, preferably in staggered relationship (Fig. 5), which belt passes around three wheels 22, 23 and 24, the drive wheel 22 being fast to the cross shaft 25 journaled in the side-frames 13 and 14 (Fig. 1), while the wheels 23 and 24 are journaled on the stub shafts 26 and 27 respectively.

The drive wheel 22 and belt 20 are driven in the direction of the arrows (Fig. 2) by the chain 28 which passes around the sprocket 29 connected with the shaft 25 by a clutch, the chain 28 also passing around the sprocket 30 mounted on the cross shaft 31 which carries the sprocket 32 driven by the chain 33 which passes around the sprocket 34 fast to the power-shaft 35 journaled in the side frames 13 and 14. As shown in Fig. 2, the chain 28 also passes around the idler sprockets 36 and 37 fastened to the stub shafts 38 and 39 respectively.

Referring to Figs. 3, 4 and 5, the drive wheel 22 carries on its peripheral tread a series of spaced-apart pins 40 which are devised to fit into the several perforations 21 in the belt 20 as the latter is actuated in its orbit around the wheels 22, 23 and 24. Each of these pins 40 has a rounded head 41 to enable the pin readily to slip into the perforations 21, and the base of each pin is contained in the hollow sleeve 42 radially set in the wheel 22 within which sleeve 42 is the coil spring 43 to form a yielding cushion seat for the pin 40, (Fig. 4). Normally the heads 41 of the pins 40 fit snugly into the perforations 21 as shown in Fig. 5 to maintain the proper alinement of the belt 20 and also to prevent slippage. Should any of the rounded heads 41 engage the margin of its perforation 21, the pin 40 will be yieldingly depressed until the other pins 40 in engagement with the belt 20 restore the normal driving relation between the belt 20 and wheel 22 to maintain the proper alinement of the belt 20 on the wheels 22, 23 and 24 to ensure accurate feeding of the sheets.

Mounted on the shaft 31 is the lower feed-roll drum 44 above which are the usual drop-rollers 45 carried by the arms 46 mounted on the stub shaft 27. The front edges of the

sheets comprising the bank 17 are kept separated by a blast of air from the nozzle 47 connected with any suitable air pump not shown: the front margins of the sheets rest on the guide plate 48 fastened to the tie rod 49 so that the front portion of the advancing sheet may be directed into the bite of roll drum 44 and drop-rollers 45 as shown in Fig. 3.

Fitted to the inner side of the perforated belt 20 along its lower run is the hollow suction shoe 50 having the transversely cut port 51 on its underface which is adapted to register with the belt perforations 21 (Fig. 3). The required suction to enable the belt 20 to separate and advance the sheets is applied to the suction shoe 50 by a suitable hose connected with the pipe 52 coupled to any suitable air-exhausting means not shown.

According to one aspect of my invention the suction is continuously applied to the suction shoe 50 which is slidable along the belt 20 and is actuated forwardly to advance the sheets after the suction has picked up the front edge of the top sheet which adheres to the exterior surface of the perforated belt 20 opposite the suction shoe 50 when retracted to its near inoperative position (Fig. 2). The top sheet is advanced by the belt 20 with the suction shoe 50 moving forwardly until the leading edge of the sheet is caught in the bite of the rollers 44 and 45 (Fig. 3) and the shoe 50 approaches the end of its forward movement.

The means for sliding the suction shoe 50 to and fro along the inner top surface of the belt 20 in timed relation with the moving belt to advance the successive sheets may be widely varied in construction:

In the present embodiment, the suction shoe 50 is fastened to the horizontal rod 53 pinned to the link 54 mounted on the collar 55 fastened to the cross shaft 56 journaled in the side frames 13 and 14. The left end of the shaft 56 (Fig. 1) carries the short arm 57 to which is affixed the stud 58 riding in the slot 59 formed in the end of the rod 60. Also pivoted to the arm 57 is the overweighted latch-pawl 61 which engages the notched latch 62 formed in the top of the rod 60 to hold the stud 58 in the lower end of the slot 59 (Figs. 2 and 3) when the parts are in latched position in the normal operation of the feeder.

The lower end of the rod 60 is pinned to the bell-crank lever 63 journaled on the stub shaft 64 fastened to the side frame 13. The lever 63 is connected by the link 65 to the end of the cam-lever 66 pinned to the side frame 13 as shown in Fig. 1. The lever 66 carries the cam-roller 67 which engages the cam 68 mounted on the cam-shaft 69 which carries the gear 70 in mesh with the gear 71 on the power-shaft 35. The coil spring 72 fastened to the adjustable sleeve 73 on the link 65 and also fastened to the side frame 13 acts to hold the cam-roller 67 in engagement with the cam 130

68 and also to force the pin 58 upwardly through the slot 59 when the latch-pawl 61 is disengaged as will be hereinafter described.

In operation at the beginning of the cycle 5 the suction shoe 50 moves from its forward (Fig. 3) to the rearward position (Fig. 2) through the cam-roller 67 riding from the low to the high part of the cam 68, such high part being sufficiently long to hold the suction shoe 50 momentarily in its rearward inoperative 10 position while the tail end of the previous sheet is being carried off through the feed rollers 44 and 45.

Then the suction shoe 50 operating through 15 the perforated belt picks up or separates the next top sheet from the bank 17, and such sheet is advanced by the belt 20 until its leading edge is carried to the bite of the rollers 44 and 45, the cam-roller 67 going into the drop of the cam 68. The shoe 50 is carried 20 forwardly not only by its suction contact with the belt 20 but also by the force of the spring 72. Since the shoe 50 in its forward movement to the left (Figs. 2 and 3) passes out of 25 the range of the pile or bank of paper after the sheet has been advanced toward or into the bite of the rollers 44 and 45, the second sheet will not be separated and advanced until the shoe 50 has again been moved into 30 its retracted position (Fig. 2).

I have also provided a manually-operated tripping mechanism to stop the feeder whenever it becomes necessary or desirable: In the present embodiment shown in Figs. 1, 35 2 and 3, the handle 74 is pinned to the side frame 14 and operates the arm 75 connected by the link 76 to the short arm 77 fast to the cross-shaft 78 journalled in the side frames 13 and 14. Secured to the shaft 78 inside the frame 13 is the cam 79 which engages the cam-roller 80 pinned to the lever 81 fastened 40 to the short shaft 82 journalled in the side frame 13. Also fastened to the shaft 82 is the trip lever 83 having its curved tip adapted 45 to contact with the lug 84 on the latch-pawl 61. The coil spring 85 fastened to the trip lever 83 and side frame 13 keeps the cam roller 80 in engagement with the cam 79 and also rocks the trip lever 83. The outer end 50 of the cross shaft 78 carries the cam face 86 which actuates the clutch lever 87 which operates the clutch collar 88 slidably mounted on the end of the shaft 25. The collar 88 carries projecting pins 89 which engage holes 55 drilled in face of the sprocket 29. The spring 90 coiled about the shaft 25 between the collar 88 and washer 91 normally holds the clutch members in engagement to operate the feeder.

In operation, the first movement of the 60 handle 74 to the right (Fig. 2) throws the cam roller 80 into the drop of the cam 79 and causes the spring 83 to pull down the trip lever 83. The lever 83 dislodges the latch-pawl 61 from the latch 62 which allows the suction shoe 50 to remain in its for-

ward position (Fig. 3) and no sheets will be fed. The last part of the handle movement will then disconnect the clutch collar 88 from the sprocket 29 on the shaft 25 and the belt 20 stops. To resume operation the handle 74 is moved to the left and the first part of the reverse stroke permits the clutch to engage at which time the belt 20 starts to travel as shown by the arrows in Fig. 2, and the last part of the handle movement shifts the cam 79 in an anti-clockwise direction which raises the trip lever 83 and allows the over-weighted latch-pawl 61 to return to its latched position with the latch 62, thereby bringing the shoe 50 again into action with both belt 20 and shoe 50 operating as a unit. Therefore by moving the handle 74, the latch-pawl 61 is thrown out of operation before the perforated belt 20 stops through the disengagement of the clutch, and when the handle 74 is thrown to start feeding the suction belt 20 will first begin its travel before the suction shoe 50 is actuated.

In the modified form shown in Figs. 6 and 7, the suction shoe 92 is held stationary 90 and contains the sliding valve 93 which is somewhat shorter than the opening of the shoe 92 resting in sealing contact with the belt 20. The valve 93 is reciprocated by a pair of rock-arms 94 (Fig. 7) having the laterally-slidable pins 95 which engage yieldingly the valve 93. The rock arms 94 are pinned to the stub shaft 96 and are actuated by the rod 53 operated by the cam 68 as hereinbefore described, the pins 95 sliding back 95 and forth in the slots 97 cut in the opposite sides of the shoe 92.

Covering the slots 97 are the washers 98 held in yielding contact with the sides of the shoe 92 by the springs 99 coiled about the pins 95 as shown in Fig. 7. By these washers 98 the interior of the shoe 92 is kept under constant exhaust pressure notwithstanding the reciprocating movements of the valve 93, which has buffer faces 100 preferably of rubber to make a tight seal against the front and rear ends of the shoe 92. In operation, Fig. 6 shows the rear end of the shoe in communication with a perforation in the belt 20 to pick up the sheet, and corresponds to the retracted position of the shoe 50 in Fig. 2. As the belt moves forwardly the valve 93 is retracted so as to afford communication at the front of the shoe 92 corresponding to the Fig. 3 position of the shoe 50. Such reciprocation of the valve 93 within the shoe 92 affords a simple and effective means in conjunction with the travel of the perforated belt 20 to separate, advance and then release the sheet when caught in the bite of the feed rollers 44 and 45, which draw the sheet forwardly from the under side of the belt 20 beneath the shoe 92.

In the modified form shown in Figs. 8 and 9, the belt 20 has its series of perforations 1130

cut in predetermined spaced-apart groups as shown in Fig. 9, and the belt 20 is affixed to a pair of chains 101 which engage with a pair of sprockets 102 (only one being shown in Fig. 8) mounted on the shaft 23. The suction shoe 103 is held stationary and the front edge of the top sheet is picked up when the forward perforations of the belt 20 reach their Fig. 8 position. The separated sheet is then advanced by the belt 20 until the leading edge is caught by the feed rollers 44 and 45 by which time the last of the perforations have traveled beyond the zone of the port 104 of the shoe 103.

15 In the modified form shown in Figs. 10, 11 and 12, the suction shoe 105 is stationary and shell-like in form; it has a rear port 106 and a forward port 107 which are adapted to register with the perforated belt 20. Within the shoe 105 is the hollow sleeve valve 108 having the transverse slotted opening 109 which coacts with the ports 106 and 107. The valve 108 is rocked by the arm 110 pinned to the rod 53 operated by the cam 68 as hereinbefore described to connect the hollow valve 108 with the perforated belt 20 through either of the ports 106 and 107. Fig. 10 shows the connection through the port 106 while Fig. 11 shows the valve 108 being rocked in a clockwise direction and midway between the two ports 106 and 107. The operation in feeding successive sheets in conjunction with the travel of the perforated belt 20 is the same as when the suction shoe 50 is reciprocated 25 in the construction shown in Figs. 1-5.

In all the forms of my improved sheet feeder, the suction is continuously applied to the chamber of the shoe riding on the travelling belt and the separation and advancement of the successive sheets is controlled either by reciprocating the shoe along the belt or by mechanism to vary the point of application of the suction through the belt either in the shoe itself or in the constantly moving belt by grouping the series of perforations in spaced-apart intervals in the run of the belt.

The foregoing construction embodies the underlying principles of my invention, but various changes or modifications may be made in the structural details without departing from the scope of my improvements. However the foregoing is sufficient to disclose the basic principles and advantages of my invention as installed in a sheet-feeder of the continuous type.

I claim as my invention:

1. In a sheet feeder, a moving suction feed-belt for separating and advancing successive sheets, and shiftable means for applying suction therethrough at different portions of the belt during its forward travel.
2. In a sheet feeder, a constantly moving suction feed-belt for separating and advancing successive sheets, and shiftable means for

applying suction therethrough at different portions of the belt during its forward travel.

3. In a sheet feeder, an endless, loop suction feed-belt arranged adjacent the top portion of a pile or bank of sheets, means for moving said belt in a forward direction, and shiftable means for varying the point of application of suction through the belt for separating and advancing the successive sheets.

4. In a sheet feeder, an endless, loop suction feed-belt arranged adjacent the top portion of a pile or bank of sheets, means for continuously moving said belt in a forward direction, and shiftable means for varying the point of application of suction through the belt for intermittently separating and advancing the successive sheets.

5. In a sheet feeder, a moving suction feed-belt for advancing successive sheets by applying suction therethrough at different portions of the belt during its forward travel, and a tripping mechanism for rendering the suction ineffective to feed a sheet and then stopping the belt.

6. In a sheet feeder, a moving suction feed-belt for advancing successive sheets by applying suction therethrough at different portions of the belt during its forward travel, and a tripping mechanism for rendering the suction ineffective to feed a sheet and then stopping the belt, said mechanism on its reverse stroke starting the belt and then applying suction thereto to restore operation of the feeder.

7. In a sheet feeder, a moving suction feed-belt for advancing successive sheets by applying suction therethrough at different portions of the belt during its forward travel, and a manually-operated tripping mechanism for rendering the suction ineffective to feed a sheet and then stopping the belt.

8. In a sheet feeder, a moving perforated feed-belt to advance the sheets, and a reciprocating suction-shoe bearing on said belt to apply suction therethrough at different portions of the belt during its forward travel.

9. In a sheet feeder, a constantly moving perforated feed-belt to advance the sheets, and a reciprocating suction-shoe bearing on said belt to apply suction therethrough intermittently at different portions of the belt during its forward travel.

10. In a sheet feeder, a perforated feed-belt, to advance the sheets, driving means for actuating the belt, and yielding means carried by the driving means to maintain a fixed relation between said belt and driving means.

11. In a sheet feeder, a moving perforated feed-belt to advance the sheets, a suction device bearing on the belt to apply suction therethrough to pick up the sheets, and means within said device to apply said suction through different portions of the belt during its forward travel.

12. In a sheet feeder, a moving perforated feed-belt to advance the sheets, a suction device having spaced-apart ports coacting with said belt to apply suction therethrough to pick up the sheets, and means within the shoe to vary the application of suction through said ports.

5 13. In a sheet feeder, a moving perforated feed-belt to advance the sheets, a suction shoe having spaced-apart ports bearing on said belt to apply suction thereto, and a valve carried within the shoe to control the suction through said separated ports.

10 14. In a sheet feeder, a moving perforated feed-belt to advance the sheets, a suction shoe having spaced-apart ports bearing on said belt to apply suction thereto, a valve carried within the shoe to control the suction through said separated ports, and means for actuating said valve to intermittently connect the suction with said ports operable through the continued movement of the feeder.

15 15. In a sheet feeder, a moving perforated feed-belt to advance the sheets, a suction shoe having spaced-apart ports bearing on said belt to apply suction thereto, and a hollow rotary valve carried within the shoe to control the suction through said separated ports.

20 16. In a sheet feeder, a moving perforated feed-belt, a suction device to apply suction therethrough, and means for advancing said suction device concurrently with the forward travel of the belt.

25 17. In a sheet feeder, a constantly moving perforated feed-belt, a suction device to apply suction therethrough, and means for advancing said suction device concurrently with the forward travel of the belt.
